UNITED STATES PATENT OFFICE

2,471,775

APPARATUS FOR SUPPLYING AIR TO
CUPOLA FURNACES

Herbert A. Reece, Cleveland Heights, Ohio

Application March 24, 1947, Serial No. 736,780

1 Claim. (Cl. 266—30)

1

This invention relates to metallurgical furnaces of the type having a plurality of tuyères and a windbox for supplying air thereto and, as one of its objects, aims to provide a novel construction and method of operation for a furnace of this kind. Although the novel construction is hereinafter described in detail by reference to a furnace of the cupola type, it should be understood that the invention is intended to include all furnaces in which air or other gas is delivered into the interior of the furnace through tuyères.

In cupolas as heretofore constructed the tuyères have usually been arranged in spaced relation in a series extending around or partially around the periphery at a level below the melting zone and the combustion air for operating the cupola has been supplied through a windbox with which the tuyères are connected. In the operation of the cupola the quality of the melt and the characteristics of the castings obtained therefrom are dependent upon the attainment of a uniform condition in the combustion zone. In the attainment of such a desired uniform condition the velocity and volume of air which slag accumulations will form on the tuyères and series are very important factors.

At times during the operation of a cupola, slag accumulations will form on the tuyères and will partially restrict the tuyère openings and alter or unbalance the air flow therethrough. Unless these accumulations are promptly removed the desired uniform condition in the combustion zone cannot be maintained. Heretofore there has been no satisfactory way of preventing such slag accumulations and once formed, they have had to be removed either by dislodging the slag by a hand-poking operation or by providing the tuyères with individual manually operable dampers which could be closed from time to time to prevent the slag to be burned away. The main disadvantage accompanying the use of such manually operable dampers is that when a damper is closed by the attendant and is not reopened within a given time the tuyère and the adjacent metal framework will become burned and the work of repairing such damage involves considerable expense as well as an idle repair period for the cupola.

The present invention overcomes this difficulty by providing an improved construction by which such accumulations of slag on the tuyères is effectively retarded or prevented during the operation of the cupola.

Another object is to provide a novel means for supplying air to a furnace through a series of tuyères in which a sequential temporary closing or restricting of the air passages to the tuyères, or to groups of tuyères, permits the slag to be

2

burned away at regular or frequent time intervals.

Still another object is to provide improved apparatus of this character in which mechanically actuated shutter means is employed for causing the temporary sequential interrupting or restricting of the air flow to the tuyères.

Yet another object is to provide improved apparatus of this character in which the tuyères are in groups and the mechanically actuated shutter means includes shutter elements associated with the respective groups and which shutter elements are sequentially movable to open and closed positions for controlling the supply of air to the tuyères of such groups.

It is also an object to provide improved apparatus of this kind in which the cupola has substantially opposed walls containing the groups of tuyères and the shutter elements are actuated in such sequence that when the shutter element controlling the tuyères of one wall are open or being opened the shutter element for the tuyères of the opposite wall will be closed.

This invention also provides improved apparatus of the kind mentioned in which variable speed means is employed for obtaining a desired rate of actuation for the movable shutter means.

Other objects and advantages of the invention will become apparent in the following detailed description.

In the accompanying sheets of drawings:

Fig. 1 is a partial end elevational view showing a furnace of the cupola type embodying the present invention;

Fig. 2 is a partial transverse sectional view taken as indicated by line 7—7 of Fig. 1, and

Fig. 3 is another partial vertical sectional view taken approximately on line 8—8 of Fig. 2 and showing one of the shutter actuating devices on a larger scale.

Figs. 1, 2 and 3 show another embodiment of the invention in which a furnace or cupola 58 of the quadrangular type has opposed side walls 59

and 60 containing groups or rows of tuyères 61 and 62. Windboxes 63 and 64 are provided on the side walls 59 and 60 and to which air is supplied for delivery to the tuyères of the respective groups. The tuyères 61 are supplied with

air from the lower end of the windbox 63 through the control openings 65 which serve the respective tuyères of this group. A similar group of control openings 66 supply air from the lower end of the windbox 64 to the respective tuyères

62 of the other group. The control openings 65 and 66 of the windboxes 63 and 64 are connected with the tuyères 61 and 62 through the tuyère boxes 67 and 68 which are here shown as being laterally continuous for serving all of the tuyères of the groups. If desired, however, the

tuyère boxes 67 and 68 can have vertical partitions therein between the adjacent control openings or each tuyère can have its own short vertical trunk of rectangular section that connects to the bottom of the windbox that supplies its group.

In this form of the invention air is supplied continuously to the two windboxes 63 and 64 but the delivery of air therefrom to the tuyère groups takes place intermittently and in sequential relation and results in the supply of combustion air being delivered into the furnace shaft alternately from opposite sides thereof. This is achieved by temporarily retarding or closing the control openings of one tuyère group while the control openings of the other group remain open, and then reversing this situation.

In the construction as illustrated in Figs. 1, 2 and 3 the openings 65 are controlled by an elongated movable shutter element 70 which is mounted on a pivot shaft 71 and is adapted to swing from a closed position overlying these openings to the upright open position as shown in Figs. 1 and 2 in which the openings are uncovered. Similarly the openings 66 are controlled by a movable shutter element 72 mounted on a pivot shaft 73. Any appropriate mechanism can be employed for causing the shutters 70 and 72 to be actuated in the desired alternate or sequential relation so that each shutter will be moved to an open position while the other shutter remains closed or restricted.

One suitable form of actuating mechanism for the shutters 70 and 72 is here shown as comprising gear-like disk members 74 and 75 which are adapted to be continuously driven in opposite directions by worm elements 76 and 77 carried by a common actuating shaft 78. This shaft is driven by a variable speed electric motor 79 through the gear 80 and motor pinion 81. The pivot shafts 71 and 73 of the shutters 70 and 72 have actuating levers 82 and 83 mounted on the ends thereof which are adjacent to the disks 74 and 75 and these levers carry projecting pins 84 and 85. The disks 74 and 75 have lugs 86 and 87 mounted thereon which, during rotation of the disks by the worm elements 76 and 77, engage the pins 84 and 85 to cause swinging of the levers 82 and 83 for temporarily moving the shutters 70 and 72 to the open position.

The disks 74 and 75 are mounted for rotation on shafts 74a and 75a which are disposed in eccentric relation to the axes of the pivot shafts 71 and 73 of the shutters 70 and 72. Because of the eccentric mounting of these disks relative to the pivot shafts, the lugs 86 and 87 will have paths of travel such that they will engage and pick up the pins 84 and 85 at points corresponding with the closed positions of the shutters 70 and 72 and will swing the levers 82 and 83 to a substantially upright position corresponding with the open condition of the shutters. During this upward swinging of the levers the pins 84 and 85 will slide across the faces of the lugs 86 and 87 and when the levers approach or reach their vertical position the levers will be released by reason of the lugs being carried over the pins. As shown in Fig. 1, the disks 74 and 75 have the actuating lugs 86 and 87 thereof spaced apart approximately 180° so that the opening of the shutters which is produced by the upward swinging of the levers 82 and 83 as just described, will take place in the desired sequen-

tial or alternate relation. It will be understood of course that the above described actuation of the shutters is carried out as a continuous cycle and that as soon as one of the lugs has lifted the corresponding shutter and has released the pin, that shutter will drop by gravity to its closed position overlying the control openings.

The rate at which the alternate or sequential actuation of the shutters 70 and 72 is carried out can be varied so as to provide a time interval of desired length during which the tuyères of each group will be supplied with air. This can be accomplished by varying the speed of the electric motor 79 as by means of the speed control device or rheostat 90. The shutter actuating disks 74 and 75 and the electric motor for driving the same can be mounted on any suitable support, such as the bracket 91, which is attached to the shell of the furnace structure. From the construction illustrated in Figs. 1, 2 and 3, and described above, it will be seen that combustion air will be supplied to the furnace shaft alternately from opposite sides thereof through the tuyère groups 61 and 62 and when one group of tuyères is temporarily closed, any slag accumulation thereon will be effectively melted off or burned away.

From the accompanying drawings and the foregoing description it will now be readily understood that this invention provides a novel apparatus by which the air supply to the tuyères of a furnace can be controlled so as to cause a temporary sequential decrease or interruption in the flow of air to the tuyères or to groups of tuyères for preventing slag accumulations on the tuyères during the operation of the furnace. It will also be understood that the invention provides a continuously operating, variable speed shutter mechanism by which the sequential temporary closing or restricting of the air passages to the tuyères or groups of tuyères can be obtained in a practical and dependable manner.

Although my invention has been illustrated and described herein in some detail it will be understood, of course, that the invention is not to be regarded as being correspondingly limited but includes all changes and modifications coming within the scope of the appended claim.

Having thus described my invention, I claim:

50 A cupola having a rectangular shaped shaft having a separate windbox on each of two opposite sides, each windbox having a set of tuyères, an air supply means to each windbox, a movable shutter means in each windbox between the air inlet and tuyères thereof, and means for operating said shutter means to alternately retard or shut off the flow of air through the tuyères of each windbox.
